his Atty.

UNITED STATES PATENT OFFICE.

GEORGE W. MILKMAN, OF NEW YORK, N. Y., ASSIGNOR TO CHARLES E. KILBOURNE, OF FAIRHAVEN, VERMONT.

COMBINATION MASSAGE-ROLLER AND EXERCISER.

SPECIFICATION forming part of Letters Patent No. 681,331, dated August 27, 1901.

Application filed May 2, 1900. Serial No. 15,220. (No model.)

To all whom it may concern:

Be it known that I, GEORGE W. MILKMAN, a citizen of the United States, residing at New York, in the county and State of New York, 5 have invented certain new and useful Improvements in Combination Massage-Rollers and Exercisers, of which the following is a specification.

This invention relates to that class of massage-rollers and exercisers which embody a series of revoluble balls relatively mounted in an elastic or fixed relationship and adapted to travel under pressure over and against the surface of various parts of the body.

One object of my invention is to provide a simple and improved device of this character which will combine in one apparatus members which are adapted for different purposes or uses and which perform different functions 20 or offices in different positions or arrangements or under various circumstances, whereby the device will be adapted for various uses, either as a massage-roller or an exerciser.

A further object of my invention is to provide a device of this character which will possess advantages in point of inexpensiveness, convenience, simplicity, adaptability, ease of operation, effectiveness, and general efficiency.

In the drawings, Figure 1 is a side view of the improved massage-roller and exerciser device embodying my invention. Fig. 2 is an edge view of the same. Fig. 3 is a perspective view showing the handle member detached and illustrating its use as an independent massage device. Fig. 4 is a detail sectional view taken on the line $x-x$, Fig. 1.

Corresponding parts in all the figures are denoted by the same numerals of reference.

Referring to the drawings, 1 designates the body portion of a massage-roller device of the class to which my invention and improvements relate or are especially adaptable. This body portion usually comprises a series 45 of balls or rollers 2, revolvably mounted in pairs or plurally upon a cross rod or wire 3, said sets of balls and their carrying-rod being arranged in a parallel or successive manner throughout the longitudinal extent of 50 the device and the rods or wires 3 being carried by longitudinal side members 4, which

are either flexible or elastic. The side members are usually converged at their ends, as at 5, and are arranged to carry handle members 6.

In carrying out my invention and improvements I preferably form the longitudinal side members 4 of a series of separate coiled springs 7, which are respectively extended between each pair of transverse ball-carrying wires or rods 3 and are detachably connected at their respective ends with said members 3, as represented at 8, this detachable connection being preferably formed by means of a hook connection. I accomplish by means of 65 the improved construction and arrangement as just stated not only a longitudinal elastic or spring movement, whereby the device may be used as a pulling exerciser, if desired, but inasmuch as the longitudinal body portion 1 70 is made up of separable sections said sections may be readily and conveniently detached or connected for the purpose of increasing or diminishing the length of the body portion of the apparatus, as desired. In lieu 75 of the springs 7 I may of course manifestly employ ordinary elastic cables or other adapted elastic members, or said members 7 of the longitudinal side members 4 may be non-elastic, if desired. The convergent end portions 80 5 for the connection of the handle members may be either flexible or elastic or formed of wire rods; but I prefer to employ elastic cords, as represented in the drawings, and I preferably provide intermediately between 85 the handle connection and the said end portions 5 a coiled spring, as at 9.

The improved handle members 6, as herein illustrated and described, are a leading feature of my invention and improvements. 90 Said improved handle members embody a cross-piece 10, preferably shaped as a handle or adapted in its contour to be grasped in the hand, and said cross-piece 10 carries a projecting body portion 11, preferably formed 95 of wire and comprising outwardly-projecting side arms or members 12, carrying or connected with or integral with a cross-rod 13. Upon the cross rod or wire 13, between the side arms 12, I mount revolvably a series of 100 balls or rollers 14. Any suitable number of balls 14 may be employed, but I have herein

shown the preferred number of three. The improved handle member 6 is detachably connected with the body member 1, this connection being provided upon the cross-piece 10 and preferably consisting of a hook 15, projecting from said cross-piece and adapted to engage a hook 16, which may integrally project from the intermediate spring 9.

The detachable handle member 6, as above set forth, forms virtually a double handle, and it is adapted for a great variety of uses, and its detachable provision enables it to be used upon various forms of massage or exercising devices and also independently used in a variety of manners as a distinct massage device. The balls 14, in connection with the outer rod 13, and the cross-piece 10 both constitute in one device handles or handholds which are adapted to be alternately or reversibly employed in accordance with the specific uses of the device 6.

When the device 6 is employed as a handle upon the form of the body member 1, as herein illustrated, of a massage-roller device or when it is employed as a handle in connection with any other form of pulling exerciser or massage device, the cross-piece 10 forms a detachable means of connection, and the rollers 14, connected with the cross-rod 13, are grasped in the hand and constitute the handle or handhold proper. When thus used, the handle proper consists, as will be noted, of a series of revoluble balls or rollers, and this is an important and advantageous feature of my invention, inasmuch as when the hand grasps said balls in the operation of the device they impart a muscle movement to the hand and fingers. When the device 6 is used as an independent massage device detached from other mechanism or apparatus, the cross-piece 10 forms the handle or handhold proper and is grasped in the hand, and the device under these circumstances is adapted to be effectively and conveniently employed in a massage operation upon the face, neck, arms, abdomen, head, hand, or other parts of the human body, the rollers 14, carried upon the outer cross-bar 13, being used as the contact-surface under pressure. The adaptability of the device 6 to the independent uses just stated is indicated in Fig. 3.

It will be understood that the balls or rollers, as at 2 and 14, may be of any suitable size or contour and employed in any desired number, and they may be constructed of wood, glass, metal, or any other suitable material. A further manifest modification of my invention consists in the revoluble mounting of the balls upon cords or elastic cables or other adapted media instead of upon rods or wire, as herein shown. It will be further noted that the detachable connection of the handle members 6 and their structural adaptability for independent use, in combination with the body-structure 1 in the composite device herein illustrated, produces vir-

tually three independent massage devices in one, thus effecting economy and enabling a wide range of utility and adaptability. 70

The operation and advantages of my invention will be readily understood by those skilled in the art to which it appertains and by reference to the foregoing description taken in connection with the drawings forming a part thereof. 75

The composite device in its entirety, as herein illustrated, is adapted for a thoroughly flexible movement in its various constituent parts, and the device 6 constitutes in its plurality of functions and alternate uses an entirely separate massage means which can be effectively employed upon all parts of the body by a simple hand rubbing or pressure movement in lieu of the ordinary hand-massage. 85

I do not desire to be understood as restricting myself to the specific features or details of construction and arrangement as herein shown and described, as manifest variations and modifications may be made in the structure and relative arrangement of the parts without departing from the spirit and scope of my invention and improvements. I therefore reserve the right to all such variations or modifications as properly come within the spirit of my invention and the terms of the following claims. 95

Having thus described my invention, I claim and desire to secure by Letters Patent— 100

1. As an improvement in massage or exercising devices of the class set forth, a handle member comprising an inner cross-piece forming a handhold and carrying positively in predetermined fixed relative arrangement an outwardly-projecting frame embodying an outer cross-piece upon which are mounted rollers, said outer cross member and its rollers constituting an outer handle or handhold, and said inner cross-piece or handhold being provided with means for attachment or connection with the body of a massage or exercising device. 105 110

2. As an improvement in massage or exercising devices of the class set forth, a handle member, comprising an inner cross-piece constituting a handhold and provided with means of attachment to or connection with the body of a massage or exercising device, 115 a substantially rigid frame projecting from said inner attachment cross-piece and embodying side members and an outer cross member, and rollers revolvably mounted upon said outer cross member between said side members, for the purpose set forth. 120 125

3. The herein-described massage or exercising device, comprising a main or body portion consisting of side members carrying a longitudinally-arranged series of transversely-mounted rollers, and a detachable handle embodying a cross-piece adapted to serve as a handhold and provided with means for attachment or connection with said body 130 135

- portion, and a substantially rigid frame projecting from said cross-piece and carrying rollers adapted to serve as an individual handhold, for the purpose set forth.
- 5 4. A massage or exercising device of the class described, comprising a main or body portion consisting of sets of transversely-mounted rollers; in combination with elastic side members connected at their ends at each 10 end of the main or body portion; and a detachable handle embodying a cross-piece adapted to serve as a handhold and provided with means for attachment or connection with the connected ends of said elastic side members at the end of the main or body portion, 15 and provided with a substantially rigid frame projecting from said cross-piece and carrying rollers adapted to serve as an individual handhold, for the purpose set forth.
- In testimony whereof I have signed my 20 name in the presence of the subscribing witnesses.

GEORGE W. MILKMAN.
